MIRROR ASSEMBLY FOR AN ARC IMAGING FURNACE

Harold L. Morian, Jr., Arlington, Mass., assignor to Arthur D. Little, Inc., Cambridge, Mass., a corporation of Massachusetts

Filed Feb. 23, 1962, Ser. No. 175,072
2 Claims. (Cl. 219—383)

This invention relates to an arc imaging furnace and more particularly to an imaging furnace which incorporates two ellipsoidal projection mirrors and one ellipsoidal reimaging mirror.

There are now available, continuous duty arc imaging furnaces which are constructed to have two radiant energy sources which are used alternately to provide a continuous source of high temperature. Conveniently the source of radiant energy is an arc formed between an anode and cathode. Normally the anode of such an arc lamp has a life of a matter of 20 minutes or so and the cathode 40 minutes or so, which means that it is necessary periodically to change the anode and the cathode if a long period of continuous operation is desired. For example in the growth of crystals under controlled conditions at very high temperatures, it is sometimes necessary to operate an imaging furnace for as much as several hours. It will be appreciated that if one is to grow single crystals in this manner it is necessary to be able to switch from one lamp source to another without any interruption in the high temperature flux. Presently the switching from one lamp to another is done by means of a flip-flop mirror which is turned first to face one ellipsoidal mirror and then another. This arrangement means that in the switch-over the radiant flux serving as the source of heat in the imaging furnace is interrupted. This is not desirable, particularly in the growth of single crystals and in some cases, makes the imaging furnace unworkable for this purpose. It would therefore be desirable to have incorporated in an arc imaging furnace, an apparatus which would permit the switching from one arc lamp to another without any interruption of the radiant flux concentrated in the working area, for example on the crystal growing apparatus. It would also be desirable to have apparatus of this character which would require no adjustment once the switching was accomplished, that is to have an apparatus which would maintain mirrors constantly in alignment. The apparatus of this invention provides such an arrangement.

It is therefore an object of this invention to provide an apparatus usable with an arc imaging furnace which permits continuous operation of the furnace while providing for replacement of the anode and cathode carbons. It is another object to provide such an apparatus which permits switching from one lamp source to another without any interruption of the high temperature flux. It is still another object to provide such an apparatus which does not require continual realignment once original alignment has been achieved. It is yet another object to provide two slidably mounted mirrors which can be automatically interchanged and which do not interrupt radiant flux in the process of changing lamps and therefore which do not rely on their operation upon a fast switching time. Other objects of the invention will in part be obvious and will in part be apparent hereinafter.

The invention accordingly comprises the features of construction, combinations of elements and arrangement of parts which will be exemplified in the constructions

2

hereinafter set forth and the scope of the invention will be indicated in the claims.

For a fuller understanding of the nature and objects of the invention, reference should be had to the following detailed descriptions taken in connection with the accompanying drawings in which:

FIG. 1 is a diagrammatic representation of a typical arc imaging furnace in which the mirror assembly of this invention is used;

10 FIG. 2 is a side elevational view of the mirror assembly; and

FIG. 3 is an end elevational view looking from the forward end.

Briefly, the mirror assembly of this invention comprises 15 a first reflecting mirror associated with a first projection mirror, a second reflecting mirror associated with a second projection mirror and adjacent the first reflecting mirror; support means adapted to hold the reflecting mirrors in a fixed and predetermined relationship to each other and to 20 their respective projection mirrors; elevated horizontal rails associated with the support means; and means for moving the support means back and forth along the rails whereby the two projection mirrors may be alternately used to project radiant energy onto a reimaging mirror without 25 interruption in the transmission of the radiant energy.

The incorporation of the mirror assembly of this invention into a typical arc imaging furnace may be seen with reference to FIG. 1. The mirror assembly itself is indicated within the dotted rectangular area 21. It 30 may, however, first be helpful to identify the primary working parts of an arc imaging furnace to better understand the construction and function of the mirror assembly.

The arc imaging furnace of FIG. 1 has two ellipsoidal 35 projection mirrors 10 and 11. In the terminology used in the description which follows the forward end of the mirror assembly will be that which is nearest the ellipsoidal projection mirror 11, i.e., the right hand mirror which functions with ellipsoidal projection mirror 10. 40 For each of the ellipsoidal projection mirrors 10 and 11 there is provided identical auxiliary equipment. The radiant energy source, generally referred to as the lamp 12, comprises a cathode 13 and an anode 14 held in spaced relationship such that when power is applied by 45 means of a power source 17, an arc is created across the gap between the cathode and the anode to furnish the source of radiant energy required. Suitable ellipsoidal projection mirror supports 18 are provided along with a cathode support and drive 15 and an anode support and 50 drive 16. Located within the main mirror supports 18 are alignment screws 19 used to effect an initial alignment of the ellipsoidal projection mirrors. The entire assembly is mounted on a base 20.

A reimaging ellipsoidal mirror 25 is used to focus the 55 radiant energy upon the work area 26 indicated generally as a focal point x. It will of course be appreciated that any of a variety of equipment may be located within area 26 such as, for example, crystal growing apparatus. Any such apparatus may be supported along a horizontal 60 support bar 27 which in turn is held in place by a mounting 28. Inasmuch as ellipsoidal mirrors 10, 11 and 25, along with their associated equipment as described above, are not part of this invention they need not be further discussed except to indicate their relation to the mirror 65 assembly of this invention.

The mirror assembly indicated in the rectangular box 21 is shown in detail in FIGS. 2 and 3. It will be appre-

ciated that it is necessary to position the mirrors 30 and 31 such that mirror 30 reflects radiant energy from ellipsoidal mirror 10 to the reimaging mirror 25. Likewise mirror 31 is associated with ellipsoidal projection mirror 11 and performs a function identical to that of mirror 30. Because the anodes 14 and cathodes 13 burn out, i.e., usually in about 20 minutes for anodes and 40 minutes for cathodes, it is necessary to alternate between the lamps, i.e., first using the left hand lamp focusing upon the forward mirror 30 and then the right hand lamps with the after mirror 31. This permits changing the anodes and cathodes regularly while at the same time providing a continuous and constant source of radiant energy at the focal point x associated with reimaging mirror 25.

By the apparatus of this invention mirrors 30 and 31 are alternately shifted into position in a manner such that no alignment is required once the original alignment of the mirrors is achieved. Moreover, as will become apparent the shifting process provides for the continual transfer of radiant energy without any interruption. Thus the necessary high temperatures may be brought to focus upon the focal point x for an extended period of time despite the limitations placed upon the length of operation of any one individual anode or cathode in the lamps.

FIG. 2 is a side elevational view of the mirror assembly of this invention, while FIG. 3 is an end view looking from the forward mirror 11 toward the after mirror 10. Focusing mirror 30, which in FIG. 2 is in front of focusing mirror 31, is mounted on a base 32 which has an inclined face, the angle of inclination being that required to cause the mirror to reflect the radiant energy from mirror 10 onto reimaging mirror 25 of FIG. 1. This mirror 30 is mounted by means of a mirror support plate 36 and by screws 33 to the mirror base 32. The mirror is affixed to the mirror support plate 36 through adjustable clips 38 and held in position by springs 40. In a similar fashion the reflecting mirror 31 is affixed to a base 34 with an inclined face. The angle formed by the two inclined faces of bases 32 and 34 will, of course, be determined by the optics of the imaging furnace. In the same manner mirror 31 has a support plate 37 and is affixed to it through adjustable clips 39. Likewise springs 41 are provided at the corners of the face of the mirror to hold it firmly to the clips.

The two mirror bases 32 and 34 are affixed to or may be integral with the housing platform 46 which has one platform extension 47 forward and two platform extensions 50 after. The single platform extension 47 is equipped with a suitable bearing 48 and is adapted to move horizontally over a bar or circular forward rail 53. Likewise the after housing extensions are similarly equipped with bearings 51 and are adapted to move horizontally over a circular after rail 54.

The forward rail 53 is in turn permanently positioned in a mounting 55 which is integral with a forward rail support 57; and in like fashion the after rail 54 is permanently positioned in a mounting 58 which is integral with a rail support 59. It will be appreciated that the rails are so affixed in the mounting and support that they do not rotate.

It will be seen in FIG. 3 that through the extensions 47 and 50 the housing platform 46 and hence the mirrors may be moved back and forth in a horizontal plane such that they alternately place mirrors 30 and 31 in appropriate positions to reflect radiant energy from ellipsoidal mirrors 11 and 10, respectively. In order to affect this horizontal motion it is necessary to provide apparatus for doing this, the apparatus being such that it may be actuated by forces external of the arc imaging furnace. There is, therefore, provided a drive wheel 62 and a wire 63 which is permanently affixed to an extension 64 of the forward platform extension 47. By turning drive wheel 62, wire 63 can be made to pull the housing platform in either direction. In order to achieve this there are also provided guide rolls 65 which are attached

to the rail supports 57 by means of suitable attaching support 66. Drive wheel 62 is mounted on a drive shaft 70 which in turn may be manually driven through a cable 71 which is coupled to the shaft 70 by a coupling 72 (FIG. 2). The shaft itself is in a housing 74 which is mounted on or integral with a support 75 which in turn is attached to the main support 20 of the arc imaging furnace. Alternately, shaft 70 and hence drive wheel 62 may be turned through the use of a sprocket wheel 78, mounted on shaft 70, and a suitable chain 79 for the sprocket wheel 78.

In the operation of the arc imaging furnace incorporating the mirror assembly of this invention we may assume first that the left hand lamp 12 is functioning and that 15 radiant energy is focused onto reimaging mirror 25 by means of mirror 30. When the time is reached that anode 14 or cathode 13 is close to being burned out, right hand lamp 12 is energized, shaft 70 is turned and mirror 30 is brought into position such that it will reflect radiant energy now derived from the right hand lamp and focused 20 from projection mirror 11 onto reimaging mirror 25. Thus in the changeover of one lamp to another there is no time in the operation when radiant energy is cut off from the focal area 26. Moreover by the proper original alignment of mirrors 30 and 31 onto their respective bases 32 and 34 no realignment is required when the mirrors are alternately shifted into position. This 25 obviously makes for efficient and continuous operation of the arc imaging furnace.

It will thus be seen that the objects set forth above among these made apparent from the preceding description are efficiently attained and since certain changes may be made in the above constructions without departing from the scope of the invention it is intended that all 30 matter contained in the above description and shown in the accompanying drawings shall be interpreted as illustrative and not in a limiting sense.

I claim:

1. An arc imaging furnace, comprising
  - (a) duplicate first and second ellipsoidal projection mirrors;
  - (b) duplicate first and second radiant energy sources positioned with respect to said projection mirrors to direct radiant energy onto said first and second ellipsoidal projection mirrors, respectively;
  - (c) a reimaging ellipsoidal mirror adapted to concentrate radiant energy upon a work area, said reimaging mirror being located above the plane of said projection mirrors and centrally positioned between them;
  - (d) duplicate first and second reflecting mirrors positioned between said first and second projection mirrors and aligned therewith, said first and second reflecting mirrors being adjacent to each other and being adapted to alternate in directing said radiant energy first from said first ellipsoidal projection mirror and then from said second ellipsoidal mirror onto said reimaging ellipsoidal mirror;
  - (e) mirror support means adapted to hold said first and second reflecting mirrors in fixed angular relationship to each other, in radiant energy receiving relationship alternately with said first and second ellipsoidal projection mirrors, respectively, and alternately in radiant energy directing relationship with said reimaging mirror;
  - (f) horizontal rails adapted to support and furnish direction of movement to said mirror support means; and
  - (g) means for moving said mirror support means back and forth along said rails whereby said first and second reflecting mirrors are movable with respect to said ellipsoidal projection mirrors and said reimaging mirror and are capable in their alternating movement of supplying said radiant energy constantly and continuously to said work area.

2. Mirror assembly in accordance with claim 1 wherein said means for moving said mirror support means comprises a rotatable drive wheel and shaft means for rotating said drive wheel.
